AIR INJECTOR FOR WATER WELL
PRESSURE SYSTEMSDale H. Birdsall, 2830 Reed Ave., Livermore, Calif.
Filed Sept. 21, 1962, Ser. No. 225,338
6 Claims. (Cl. 103—6)

The present invention relates in general to a device for recharging the air volume in a water well pressure system, and in particular to a device for injecting air into, and thus maintaining sufficient air volume in, a pressure tank of the type which depends upon a cushion of air for proper operation.

In domestic water systems, water is pumped into a pressure tank at a point near the bottom thereof. As the water rises, the air already in the tank is compressed against the upper end of the tank. The system is provided with a means for automatically stopping the water pump at such time as the pressure of the compressed air reaches a preset value. The air thus compressed provides a cushion which will deliver, under pressure, a substantial part of the water in the tank (with an accompanying drop in pressure), before the pump resupplies the tank with water.

An inherent problem of such water systems is that the pressure tank tends to lose part of such cushion of air (e.g. due to absorption by the fresh water, leaks, etc.) after a period of time. The reduction of air cushion volume causes the pumping "on" time to become shorter, and results in less water being pumped into the tank during each part of the "on" cycle. The air cushion can become so small in volume that the pumping operation resolves into a continuous "start" and "stop" operation of the pump.

There are several devices of varying configurations and theories of operation for solving the problem of air cushion loss in commercial use at the present time. In general, however, such devices comprise a complicated maze of inter-coupled components which are expensive to install and which are particularly difficult, time consuming and cumbersome to service. A prior art device of simple construction is in use at the present time, but is extremely difficult to service. Such device utilizes two orifices, which are inserted in the water supply pipe of a water system to drain a section of the pipe and replace the water with air during the "off" cycle of the pump. Since the orifices are located below the well cap the entire supply pipe and attached pump must be raised sufficiently to permit servicing. This is a difficult and time consuming operating, requiring heavy equipment and necessitating disassembly of portions of the water supply pipe. In this prior art device it is furthermore extremely difficult to alter the amount of air introduced to the pressure tank during each cycle. Since most air recharging devices require periodic cleaning and/or servicing, it is particularly advantageous and desirable to replace the above-mentioned complicated prior art devices (or those devices which are difficult to service) with an inexpensive air charging device of simple construction, which any layman can install and periodically service with a minimum of labor, effort and expense.

The present invention solves not only the old problem of recharging the air cushion (volume) in a water well pressure system tank, but does so in an exceedingly simple and straight-forward manner. In theory, means are provided to siphon a volume of water from the upper end of the water supply pipe of a water well system, and to replace such volume with a quantity of air. Upon operation of the pump the quantity of air is prevented from escaping to the atmosphere and is delivered along with the water being pumped, to the pressure tank thereby replenishing any losses in the air cushion volume therein.

2

Therefore, it is an object of the present invention to provide a means for periodically recharging the air volume in the pressure tank of a water well pressure system.

It is another object of the present invention to provide 5 a pressure tank air recharging device which may be readily installed and serviced with a minimum of expense and effort, in either existing or new water wells.

It is yet another object of the present invention to provide 10 a pressure tank air charging device, which can be set to deliver a predetermined quantity of air to a pressure tank with a minimum of effort, during or after initial installation thereof.

It is a further object of the present invention to provide 15 a means for siphoning a predetermined volume of water from a water pressure system, and replacing such volume of water with air, which air is then delivered to the pressure tank.

It is yet a further object of the present invention to provide 20 a pressure tank air charging device which can be serviced without necessitating the removal of the water well supply pipe from within the well casing.

It is still another object of the present invention to provide 25 an air charging device which is unaffected by temperature changes or various water conditions.

Further objects and advantages will be apparent in the 30 following description and claims considered together with the accompanying drawing, in which:

FIGURE 1 is a cross-sectional view of the present invention as installed in a submersible pump water pressure 35 system during the "off" cycle thereof.

FIGURE 2 is a cross-sectional view of a portion of the 40 invention apparatus showing a modification thereof.

Referring to the drawing, a submersible pump 10 is 45 connected to the bottom end of a water supply pipe 12, which pipe extends from ground level to near bottom of a water well 14, within a well casing 16. Casing 16 is provided with a casing cover 18 at its upper end. The upper end of water supply pipe 12 extends through a hole in the center of casing cover 18, and is threaded to a standard pipe T 20. The 90° outlet of the T 20 is coupled by means of a nipple 22 to a swing check valve 24. A pressure tank pipe 26 is connected to the swing check valve 24, and provides means for delivering water from submersible pump 10, through pipe 12 and swing check valve 24, to a pressure tank 27.

The remaining outlet of pipe T 20 has threaded thereto 50 a connecting nipple 28, which has in turn a cap 30 threaded thereon. A check ("air snifter") valve 32 is secured to a hole through the cap 30 by means of a suitable connection, such as pipe 34. A breather vent 36 is provided on the check valve 32; the combination of valve 32, pipe 34 and vent 36, operating to introduce air into an upper volume 38 of the water supply pipe 12, as further 55 described infra. The action of check valve 32 is to pass air downwardly into the water supply pipe 12 while preventing the passage of water from the system water line to the atmosphere.

One end 40a of a siphon tube 40 (which preferably 60 may comprise a length of copper tubing bent in the general shape of a U) is extended through a second hole in the cap 30 through T 20 and into the upper end of pipe 12; that is, tube 40 is extended into (and defines) the volume 38 of pipe 12. The extent of volume 38 is determined by the distance which such end 40a is inserted into the pipe 12. A packing gasket seal 42 and (slip-joint) packing nut 44 are provided (in conjunction with a proper seal in cap 30) to insure an easily demountable air-tight connection between the tube 40 and the cap 30.

The other end 40b of siphon tube 40 extends downwardly, preferably through a hole in the casing cover 18, to protrude into the annular volume between casing 16

and supply pipe 12. A "leak" check valve 46 is attached to the end 40b of siphon tube 40, and is positioned lower than the opposite end 40a thereof. "Leak" valve 46 can be simply a restricted orifice of constant diameter (i.e., can be achieved by pinching the end 40b of tube 40), or can be a differential ball check valve whose seal seat is slightly deformed to purposely allow leakage of a small quantity of water therethrough when the pump is operating and the differential ball check valve is in the closed position. A "sanitary" seal 48 is provided on casing cover 18 to prevent entrance of dirt, insects, and the like between tube 40 and casing cover 18. The seal 48 does not have to be air-tight, and can be any type of nut, cover, or packing which is readily demountable and which will prevent entrance of foreign matter into the well 14. As shown in FIGURE 1, tube 40 may be constructed in three parts; two straight lengths of tubing and one pre-formed return bend attached thereto in airtight relation, preferably by means of compression fittings of the type used in refrigeration systems.

The swing check valve 24 is a standard check valve as utilized in submersible water pressure systems. Upon operation of pump 10 valve 24 opens to allow the passage of water therethrough into the pressure tank 27. When pump 10 stops, the pressure within the tank 27 forces a swing gate 50 within valve 24 against a seat therein to thus isolate pipe 26 and the pressure tank 27 from the rest of the system.

In operation of a pressure system in accordance with the concept of the present invention, when submersible pump 10 starts, water flows therefrom up supply pipe 12, through the gate 50 in valve 24 (as shown in phantom line in FIGURE 1) through pipe 26 and into the pressure tank 27. Simultaneously, water is forced into the end 40a of siphon tube 40 and the tube 40 is filled. During operation of the pump (during the "on" cycle), a small (and negligible) amount of water is forced through tube 40 and the "leak" check valve 46, and is returned to the well 14 down the annular region between casing 16 and supply pipe 12. During the "on" cycle, the check valve 32 is closed by water pressure thereagainst to prevent water from passing therethrough. When the pump 10 stops, the gate 50 of valve 24 closes due to back-pressure from the tank 27, and the check valve 32 opens due to the lack of water pressure thereagainst. Thus siphon tube 40 continues its siphon action (since the upper end of pipe 12 is open to atmospheric pressure) and water is passed therethrough by way of "leak" valve 46 during the pump "off" cycle. The rate of water leakage (during the pump "on" cycle) or of water siphoned (during the pump "off" cycle) is regulated by the size of the orifice of "leak" valve 46. The siphon action continues until the water level within pipe 12 reaches the bottom of end 40a of the siphon tube 40, at which point the siphon action ceases. As mentioned supra, the siphon action is generated by allowing air at atmospheric pressure to enter pipe 12 through the check valve 32, whereby the volume of water siphoned through tube 40 is replaced by a like volume of air (volume 38 herein).

Upon subsequent operation of pump 10, check valve 32 is closed by the water pressure and the slug of air entrapped in volume 38 is forced through swing check valve 24 and into the pressure tank 27 along with the water pumped from the well 14. Such slug of air is forced into the pressure tank each time the pump goes through a pumping "on," "off" cycle.

It may be seen from FIGURE 1 that the size of the volume 38 (i.e., the size of the slug of air) can be varied simply by increasing or decreasing the distance that end 40a of tube 40 extends into the pipe 12. However it is to be understood that end 40a of tube 40 may be extended into the pipe 12 with no regards as to the extent of volume 38, and end 40b instead may be extended a predetermined distance downwardly along pipe 12, as indicated in FIGURE 2 by numeral 40c. Thus, at such time as the water

inside pipe 12 is siphoned down to a level 52 of end 40c outside of pipe 12, as shown in FIGURE 2, the siphoning action of tube 40 will cease as heretofore described. To prevent introducing an excessive amount of air into tank 27, an air level controller, or air bleeding valve, similar to those conventionally used in pressure systems, can be mounted in the wall of the pressure tank. Any excess of air delivered to the tank is thus vented to the atmosphere.

While the invention has been described herein with respect to several embodiments, it will be apparent that numerous variations and modifications may be made within the spirit and scope of the invention, and thus it is not intended to limit the invention except by the terms of the following claims.

What is claimed is:

1. A pressure tank air charging device for use in a water well pumping system including an air-tight pressure tank, a submersible pump, a water supply pipe extending from said pump to said pressure tank and a water check valve disposed in said supply pipe in the region thereof near said pressure tank, said device comprising a siphon tube having one end extending downwardly a substantial distance through an upper portion of said supply pipe and in sealed relationship therewith, said siphon tube and supply pipe defining an annular volume therebetween, air valve means connected to said upper portion of supply pipe in communication with said volume, said air valve being adapted to open and introduce air into the pipe at such time as said pump is inoperative, said siphon tube to siphon a quantity of water from said supply pipe upon introduction of air through said air valve means, such quantity being commensurate to said volume therein and determined by the extent of said siphon tube end therein, said air valve means to close upon operation of said submersible pump to trap the air introduced to said supply pipe.

2. A pressure tank air charging device for use in a water well pressure system including a water supply pipe, a well casing, a pump, and a swing check valve, said supply pipe and casing defining therebetween an annular region, said device comprising a pipe T having one of its outlets coupled to the upper portion of said supply pipe and a second of its outlets coupled to said swing check valve; a siphon tube having one end thereof disposed in air-tight relation through a third outlet of said pipe T and into said supply pipe; the other end of said tube extending into the annular region between said supply pipe and the casing of said water well; and a check valve coupled in air-tight relation to said upper portion of said supply pipe and adapted to introduce air at atmospheric pressure into the supply pipe at such time as said pump is turned off.

3. A pressure tank air charging device for use in a pressure system having a submersible pump connected to a water supply pipe comprising a siphon tube having a first and a second end, said first end extending into an upper portion of said supply pipe a substantial distance, said second end extending upwardly from said supply pipe to terminate at a position lower than that of said first end, said second end having a water restricting orifice secured thereto, a check valve coupled to said upper portion of said supply pipe to introduce air at atmospheric pressure to said supply pipe at such time as said pump is turned off to cause said siphon tube to siphon water from said supply pipe and replace same with air.

4. A pressure system air charging device for use in a submersible pump water pressure system having casing, a water supply pipe, a pump, and a swing check valve, wherein said casing and pipe define therebetween an annular region, said device comprising a pipe T having one outlet threaded to said supply pipe and a second outlet threaded to said swing check valve; a nipple demountably sealed to a third outlet of said pipe T; a cap demountably sealed to said nipple; a siphon tube having one end thereof disposed in air-tight relation through said

cap and extending a predetermined distance through said T and into a portion of said supply pipe; a leak valve secured to the other end of said siphon tube; wherein said other end of the siphon tube is extended into the annular region between said supply pipe and said casing to a position lower than the end which is in the supply pipe; and a check valve coupled to said cap and adapted to open when said pump is inoperative to introduce air into said supply pipe, said check valve to close upon operation of said pump to trap said air within said supply pipe and deliver same to said pressure tank.

5. A pressure tank air charging device for use with a submersible pump water pressure system having a water supply pipe extending from the submersed pump to the pressure tank and including a water check valve disposed in-line within said supply pipe, said device comprising, a siphon tube having an end extending a substantial distance into an upper portion of said supply pipe in sealed relationship therewith and at a point therealong relatively near said check valve and between said check valve and said pump, said siphon tube having another end extending downwardly exterior of said supply pipe, wherein the distance from a horizontal plane passing through the vertical termination of said first mentioned end of said siphon tubes to said check valve defines a substantial volume within said upper portion of the supply pipe, air valve means connected to the upper portion of said water supply pipe in communication with said substantial volume therein and adapted to introduce air to said substantial volume at such time as said pump is inoperative, said siphon tube to provide a siphoning action for removing the water contained in said substantial volume

- 10 6. A pressure tank air charging device for use in a pressure system having a submersible pump connected to a water supply pipe comprising a siphon tube having a first and a second end, said first end extending into an upper portion of said supply pipe a substantial distance, said second end of said siphon tube extending downwardly along said supply pipe a substantial distance to terminate at a position higher than the termination of said first end, said second end having a water restricting orifice secured thereto, a check valve coupled to said upper portion of said supply pipe to introduce air at atmospheric pressure to said supply pipe at such time as said pump is turned off to cause said siphon tube to siphon water from said supply pipe and replace same with air.
